UNITED STATES PATENT OFFICE.

ALLEN J. COUGHENOUR, OF FORT LEAVENWORTH, KANSAS.

DETECTOR.

1,115,902.

Specification of Letters Patent.

Patented Nov. 3, 1914.

Application filed January 24, 1914. Serial No. 814,211.

To all whom it may concern;

Be it known that I, ALLEN J. COUGHENOUR, citizen of the United States, residing at Fort Leavenworth, in the county of Leavenworth and State of Kansas, have invented certain new and useful Improvements in Detectors, of which the following is a specification, reference being had to the accompanying drawings.

10 This invention relates to certain improvements in wave responsive devices or as they are commonly known in the art, detectors, for use in wireless signaling systems, and relates more particularly to those systems in
15 which the energy representing the signals or message is transmitted through the natural media in electroradiant form.

20 The primary object of the present invention resides in the provision of a device of the above character embodying a mass of crystal or other metal or substance of high electrical conductivity, a renewable metal contact member, and improved means for mounting and adjusting said member to engage the same with different points on the 25 surface of the crystal mass.

The invention has for a further object to provide improved means for regulating the pressure of a metal contact needle with the 30 conducting crystal.

The invention has for still another of its objects to produce a device of the above character whereby the presence of electrical radiations may be detected with a great degree 35 of sensitiveness, such desirable result being attained without complicating the construction or increasing the cost of manufacture of such devices as they are now known and commonly employed in the art.

40 With the above and other objects in view
as will become apparent as the description
proceeds, the invention consists in certain
constructions, combinations and arrange-
ments of the parts that I shall hereinafter
45 fully describe and claim.

For a full understanding of the invention, reference is to be had to the following description and accompanying drawings, in which—

50 Figure 1 is a side elevation of a detector embodying my invention in its preferred form; Fig. 2 is a top plan view thereof; Fig. 3 is a section taken on the line 3—3 of

Fig. 1; Fig. 4 is a detail section of the stationary electric wave receiving member employed in the bi-crystal form of the detector; Figs. 5 and 6 are detail views of modified forms of certain parts of the detector.

Referring in detail to the drawings, 5 designates a suitable base of insulating material upon which the binding posts 6 are mounted, said binding posts being wired to the receiving apparatus in the usual manner. The base 5 is provided with a central opening 7 through which the receiving antenna 8 passes. The receiving antenna 8 is supported by a support 9 which is secured to the base 5. The receiving antenna 8 is connected to the receiving apparatus in the usual manner.

The post or standard 7 is also mounted upon one end of the base 5 and is provided adjacent its upper end with a transverse opening to receive the cylindrical rod or stem 8 of a holding cup 9 for the chalcopyrite or other crystal mass having the requisite electrical conductivity indicated at 10. A binding screw 7' is threaded in the upper end of the standard 7 for engagement with the rod 8 to secure the crystal conductor 10 in position. This crystal mass is securely held in a fusible metal base arranged in the cup or holder 9. The contact surface or face of this conducting medium is preferably of a very rough character, thereby presenting a multiplicity of minute contact surfaces and

multiplicity of minute contact surfaces and materially increasing the general utility and 80 serviceability of the device. Adjacent the opposite end of the insulating base 5, a plate 11 is secured thereto, said plate having the

11 is secured thereto, said plate having the vertical parallel arms 12 which constitute supporting bearings or standards for the 85 spherical member 13 in which the rod 14 is loosely mounted. One end of this rod is threaded to receive a nut 15 and the contact needle carrying member 16. This member is disposed upon the extremity of the 90 threaded portion of the rod and is horizontally arranged in parallel relation to the

arranged in parallel relation to the base. The opposite ends of said member are provided with spring clamping tongues 17 in either of which the metal contact needle 18 is securely held. Upon the rod 14 between the spherical enlargement 13 thereof, and the nut 15 a coil spring 19 is arranged.

and the nut 15, a coil spring 19 is arranged. By adjusting the nut 15 upon the rod, the tension of the spring 19 may be regulated 100 as desired to secure greater or less pressure of the point of the needle 18 against the rough face of the crystal mass 10. Upon the outer end of the rod 14, a knurled head or finger piece 20 is secured whereby said rod 105 may be readily moved by the operator in

order to engage the needle with a desired point upon the surface of the crystal conductor 10.

The binding posts 6 and 7 being connected by suitable leads in the receiving circuit of the apparatus, the electroradiant waves are transmitted through the crystal conducting mass 10 and the contact needle 18 which is engaged therewith to the receiver, the wave oscillations being converted into a form suitable for intelligently transmitting the message without necessitating the use of any auxiliary energy, and without undue resistance due to imperfect contact. The operator without removing the receiver from the head may readily adjust the position of the needle 18 upon the face of the crystal conducting medium 10 by simply pulling slightly upon the rod 14 and swinging the same in any desired direction between the bearing arms 12 whereby the point of the needle may be disposed upon a "live" point of the contact surface. In this manner, I am enabled to obtain by means of my device, without interrupting for any appreciable length of time, the transmission of the electromagnetic waves, a maximum degree of efficiency in the operation of the instrument. It will further be apparent from reference to Fig. 2 that if desired, two of the metal contact needles may be employed, and arranged in the member 16 upon opposite sides of the universally movable rod 14. The simple adjustment of the nut 15 effects a greater or less pressure of the needle point against the contact points of the electrical conducting medium 10.

In some instances, it is desired to substitute for the metal needles 18, a crystal conductor of the same or different character than the stationary crystal mass 10, so as to obtain a greater area or contacting surface between the two conductors. To this end, I provide as a substitute for the needle, the movable contact member shown in Fig. 4 of the drawings, which consists of a cup 21 having a rod 22 fixed thereto. A fusible metal 23 is arranged in the cup 21 by means of which the crystal 24 is securely held in place, said crystal being of irregular form and projecting out of the open side of the cup 21. This crystal contact member is arranged in the holding device as will be readily understood from the foregoing description, and said crystal having a plurality of contact points, will engage with several points on the roughened face of the stationary crystal mass 10.

In Fig. 5 of the drawings, I have shown a slightly modified form of the post or standard 7, in which the stationary conductor is mounted. In this construction, the standard 25 is of rectangular form and

is provided upon its upper end with the resilient tongues 26 for clamping engagement upon the rod or stem of the cup or container for the stationary conductor.

In Fig. 6 of the drawings, I have illustrated in lieu of the adjustable collar or nut 15, for regulating the tension of the spring 19, a sleeve 27 which is loosely mounted upon the rod 14'. This sleeve carries a spring plate 28, the end of which is adapted for engagement in any one of a series of notches 29 formed in the periphery of the rod. It will be readily understood that by simply sliding the sleeve 27 along the rod 14', the tension of the spring may be increased or decreased as desired and the pressure of the contact needle against the face of the stationary conductor varied accordingly.

From the above description, it is thought that the construction, manner of use and several advantages of my invention will be fully apparent.

The device effectually fulfills in a satisfactory manner, all requirements of detectors employed in wireless telegraphy, as to sensitiveness, speed, and stability. The device is in no wise affected by changes in atmospheric temperature nor is its sensitiveness appreciably impaired by long continued use. It will be understood that the crystal having the inherent property of conductors will make an operative contact with another suitable conductor, if such contact be substantially perfect. My invention requires no auxiliary source of heat as do some of the common detectors now upon the market designed for receiving high frequency oscillations. Thus a distinct commercial advantage is attained in that all auxiliary devices such as batteries and the requisite accompanying potentiometers are dispensed with, thereby eliminating a considerable item of expense. My invention is also capable of manufacture at very small cost owing to its extremely simple construction.

While I have shown and described the preferred construction and arrangement of the several elements it will be understood that the device is susceptible of considerable modification therein and I therefore reserve the privilege of resorting to all such legitimate changes as may be fairly embodied within the spirit and scope of the appended claim.

Having thus described the invention, what is claimed is:

In a detector, a stationary conductor, a universally movable support, a rod loosely mounted in said support for movement therethrough, said rod being threaded at one end, a holder detachably engaged upon the threaded end of the rod, a conductor

removably mounted in said holder and adapted for engagement with the stationary conductor, a spring mounted upon said rod and bearing against the support at one of its ends, and an adjustable nut threaded upon the rod with which the other end of said spring is engaged whereby said rod is yieldingly held against movement in one direction through its support and the pres-

sure of the conductor carried thereby upon the stationary conductor regulated.

In testimony whereof I hereunto affix my signature in the presence of two witnesses.

ALLEN J. COUGHENOUR.
